UNITED STATES PATENT OFFICE

2,608,187

UPPER CYLINDER LUBRICATOR

Frederick MacLean Stewart, Edinburgh, Scotland

Application December 19, 1947, Serial No. 792,654
In Great Britain November 20, 1946Section 1, Public Law 690, August 8, 1946
Patent expires November 20, 1966

5 Claims. (Cl. 123—196)

1

This invention has for its object to provide for the lubrication of the cylinders of internal combustion engines when starting from the cold state, by supplying a measured quantity of lubricating oil to the cylinders of the engine when the normal pressure lubricating system of the engine is not functioning efficiently owing to the high viscosity of the cold lubricating oil.

My invention consists in the method of effecting cylinder lubrication which comprises mixing lubricating oil with the fuel charge prior to admission of the combustible charge into the engine cylinder, the lubricating oil being admixed with the fuel charge automatically either prior to or after carburetting of the fuel.

My invention also consists in a method of mixing lubricating oil with the fuel comprising inducing or injecting a supply of lubricating oil into a liquid fuel passage or chamber for admixture with the fuel therein, in order to provide a mixed charge of oil and fuel for starting purposes, and regulating the oil supply to reduce or cut-off the supply of oil admixed with the fuel during normal running of the engine.

The admixture of oil and fuel may be effected by mechanical, hydraulic, electric, manual or gravity-actuated means or by any combination of such means.

The method of the present invention may be arranged to give a continuous supply of upper cylinder lubricant admixed with the fuel charge during normal running of the engine, with an additional supply of oil admixed with the fuel for starting from cold, or it may be arranged to supply oil to the fuel for starting purposes only. The oil supplied to the fuel may be regulated in order to supply a measured quantity within a predetermined time period or to control the supply of oil during normal running of the engine.

My invention further consists in apparatus for introducing a supply of lubricating oil into the engine cylinder with the combustible mixture comprising an oil chamber, a mixing chamber or mixing passage interposed in the liquid fuel supply to the engine cylinders, and means for delivering a measured or regulated quantity of oil to the mixing chamber or mixing passage from the oil chamber for admixture with liquid fuel in the mixing chamber or mixing passage.

The method of the present invention and various ways in which it may be carried into effect are hereinafter explained with reference to the accompanying drawings whereon Figs. 1, 2, 3 and 4 are views in sectional elevation of four different constructions of cold start lubricating apparatus according to the invention.

Figs. 5 to 11 are diagrammatic illustrations showing the manner in which the cold start lubricating apparatus may be incorporated in the engine fuel supply system.

6 Figs. 5 and 6 illustrate the adaption of the apparatus shown in Figs. 1 and 2 respectively.

Figs. 7 and 8 show alternative arrangements for the installation of the apparatus shown in Fig. 3.

10 Figs. 9, 10 and 11 illustrate three alternative arrangements for the installation of the apparatus shown in Fig. 4.

Referring firstly to Figs. 1 and 5, which illustrate one manner of carrying out the invention, the apparatus shown in Fig. 1 and designated by

15 the general reference character L in Fig. 5 must be positioned above the level of a fuel supply tank T between the latter and a fuel pump P which supplies fuel from the tank T to the engine cylinders or carburetter of an engine E, because the apparatus shown in Fig. 1 relies on the suction of the pump P lifting the fuel from the tank T to the lubricating oil vessel L. As shown in Fig. 1, the vessel L is provided with a fuel inlet

20 connection 1 for connection by an inlet pipe 2 to the fuel tank T. The inlet connection 1 communicates with a fuel inlet port 3 which opens into a mixing chamber 4 located within the vessel L through a vacuum passage or chamber 5 formed by a vertical tube 6 which has an oil inlet orifice 7 in its upper end. The oil inlet orifice 7 is formed in the base of an oil cup 8 which forms the base of a drip feed chamber 9 enclosed by a cover 10. An oil feed pipe 11 opens into the drip chamber 9 and is in communication

25 at its lower end with an oil chamber 12 provided in the vessel L and separated from the mixing chamber 4 by a partition 13. A filling orifice 14 fitted with a filler cap 15 enables the chamber 12 to be charged with lubricating oil.

30 The mixing chamber 4 has an outlet tube 16 which extends up through the oil chamber 12 and communicates with an outlet port 17 for connection by means of an outlet connection 18 to a mixture delivery pipe 19 which is connected to the fuel pump P. With this arrangement, the suction of the pump P draws mixture or liquid fuel from the mixing chamber 4 which is fed from the fuel tank T through the vacuum passage 5, inducing oil thereinto through the oil inlet orifice 7 from the oil chamber 12.

35 The orifice 7 may, if desired, be fitted with an adjustable needle valve or other regulating device. When the pump P is not in operation, fuel in the pipe 2 tends to return to the tank T, thus creating a partial vacuum in the passage 5 and

40 45 50 55

maintaining the flow of oil thereto through the orifice 7 until the fuel level in the pipe 2 falls to the level of the fuel in the tank T. The volume of that part of the inlet pipe 2 which extends up from a level coinciding with the level of the fuel in tank T to the inlet connection 1 thus determines the quantity of oil which is maintained in the vacuum passage 5 when the engine is not in operation. This oil is drawn into the mixing chamber 4 to mix with the fuel therein when the engine is started, and passes through pipe 16 and outlet port 17 to the engine cylinders. This oily mixture is subsequently followed by a normal running mixture having a reduced proportion of oil to liquid fuel.

Fig. 2 illustrates a modified form of the apparatus illustrated in Fig. 1 to enable the vessel L to be mounted above or below the level of the fuel tank T, or, as shown in Fig. 6 at the same level. In this case the fuel supply to the vacuum passage 25 constituted by a tube 20 is controlled by a suction valve 21 which opens into the passage 25 and is controlled by a spring 22 or otherwise loaded. The fuel enters by way of an inlet connection 24 through the suction valve 21 into vacuum passage 25 and oil is drawn into the passage 25 through the orifice 7. The mixture of oil and fuel then passes out through a port 26 in the tube 20 into the mixing chamber 4 and through a tube 27 and outlet connection 28 to the fuel pump and engine. When the fuel pump ceases, on stopping the engine, oil continues to flow into the passage 25 until the pressures above and below the orifice 7 balance each other. The suction in the passage 25 and the volume of the said passage control the maximum quantity of oil stored therein for re-starting the engine. The rate of oil flow decreases as the pressure differences above and below the orifice 7 equalize each other. When the engine is started, the fuel pump P draws fuel from the mixing chamber 4 and this is replaced by stored oil from the passage 25 until the pressure drops sufficiently to open the suction valve 21. This resultant fuel-oil mixture rich in oil is delivered to the engine for starting purposes. The mixture of fuel and oil becomes progressively weaker in oil as the normal amount of fuel enters the mixing chamber 4, until a normal mixture for normal running of the engine is attained.

In the examples hereinbefore described with reference to Figs. 1 and 2, oil is continuously supplied with the liquid fuel during normal running of the engine, and a richer oil mixture (the richness of which depends on the period up to a predetermined limit during which the engine is not in operation); is supplied when starting the engine.

According to the form of the invention illustrated in Fig. 3 oil is supplied for starting only, and the vessel L can be fitted on either side of the fuel pump P as shown in Figs. 7 and 8, or it may be used with a gravity fuel supply, in which case the pump P may be omitted. The mixing chamber 4 in the construction shown in Fig. 3 is above the oil chamber 12 and is fitted with fuel inlet and outlet connections 29 and 30 respectively. A cylinder 31 within the vessel L communicates with the mixing chamber 4 through a valve 32 which is controlled by a spring 33 or otherwise loaded and opens towards the mixing chamber 4. The valve 32 controls an oil passage 34 leading from a chamber 35 formed in the upper end of the cylinder 31, and the chamber 35 communicates with an oil supply pipe 36, the

inlet orifice 37 of which communicates with the oil chamber 12 and is fitted with a check valve 38. A piston 39 in the cylinder 31 is acted upon by the pressure of oil supplied through an oil inlet connection 40 from the usual engine-driven oil pump 46 of the normal lubricating system of the engine E through a pipe 41 as shown in Figs. 7 and 8. Above the piston 39 is fitted a spring 42 or other loading means. When the engine is stopped, the spring 42 moves the piston 39 downwards, thus drawing in oil from the chamber 12 through the oil pipe 36 into the cylinder 31. When the engine is started, the pressure in the pipe 41 acting on the underside of the piston 39 forces the oil in the cylinder 31 into the mixing chamber 4 to mix with the fuel therein, the fuel being either induced into the chamber 4 by the fuel pump P in Fig. 8 or supplied by gravity or by a fuel feed pump as in Fig. 7. The mixture of oil and fuel delivered to the engine through the outlet connection 30 becomes gradually weaker in oil until finally only liquid fuel enters and leaves the mixing chamber 4. In the construction shown in Fig. 3, the liquid fuel enters the chamber 4 through an inlet tube 43 which extends downwards from the inlet connection 29 and opens into the lower part of chamber 4. The oil chamber 12 is charged with oil through a filler 44.

The arrangement described with reference to Fig. 3 may be modified by the omission of the mixing chamber 4 as shown in the arrangement according to Fig. 4 in which the oil is directly injected into one of the fuel supply passages delivering fuel to the engine cylinders or carburettor, and is supplied only when starting the engine. This arrangement can be fitted to either side of the fuel pump P as in Fig. 9 or 10 or as diagrammatically illustrated in Fig. 11. In this case the oil is fed into a fuel supply passage at a predetermined rate. For this purpose the oil pressure pipe 41 connects the usual engine-driven oil pump 46 on the engine E to the oil inlet connection 40 which opens into the cylinder 31 below the piston 39, so that oil delivered by the oil pump 46 moves the piston 39 upwards against the pressure of the spring 42. On stopping the engine, the spring 42 moves the piston 39 downwards and draws oil through the pipe 36 and check valve 38 from the oil chamber 12. When the engine is re-started, the engine oil pressure in pipe 41 forces piston 39 upwards, discharging the oil in chamber 35 past the spring-controlled valve 32 into and through a restricted passage 45 in an outlet connection 47 which delivers the oil through a delivery pipe 48. As shown in Fig. 9 the pipe 48 is connected to a pipe 49 between the fuel pump P and the engine, but it may be connected to the fuel pump suction pipe 50 as in Fig. 10, or in cases where the fuel is supplied to the engine carburettor or to a fuel injection pump as in Fig. 11, the pipe 48 opens into the engine inlet or induction manifold 51.

The invention is not limited to the specific forms illustrated in Figs. 1 to 4 of the accompanying drawings which are capable of variation without departing from the invention. For instance, the mixing chamber 4 may be arranged externally of the vessel L instead of being located within the vessel as in Figs. 1 to 3; also the outlet connection 18 in Fig. 1 may open out direct from the upper part of chamber 4 in Fig. 1; moreover, instead of the arrangements shown in Figs. 3 and 4, the cylinder 31 and its associated elements may be arranged outside the vessel L; furthermore,

the valve 32 may be adjustably loaded, such as by adjustment of the pressure of the spring 33, so that the valve 32 acts as an adjustable pressure reducing valve, or the passage 45 in Fig. 4 may be fitted with an adjustable needle valve or other regulating device.

I claim:

1. Apparatus for effecting cylinder lubrication in an internal combustion engine comprising a mixing chamber having a fuel inlet port, a mixture delivery port, a check valve controlling said inlet port, a vacuum passage communicating with said mixing chamber, an oil inlet orifice opening into said passage, and an oil reservoir in communication with said orifice.

2. Apparatus for effecting cylinder lubrication in an internal combustion engine comprising an oil reservoir, a vacuum chamber, an oil cup, a restricted oil feed passage connecting said chamber and oil cup, an oil feed pipe from said reservoir to said oil cup, a mixing chamber, an outlet from said vacuum chamber to said mixing chamber, a fuel inlet to said mixing chamber, a valve for closing said fuel inlet and opening under withdrawal of liquid from said mixing chamber, and a delivery outlet from said mixing chamber to the engine cylinders.

3. Apparatus for effecting cylinder lubrication in an internal combustion engine comprising an oil reservoir, a vacuum chamber, a restricted oil feed pipe from said reservoir to said vacuum chamber, a mixing chamber, an outlet from said vacuum chamber to said mixing chamber whereby oil is supplied to said mixing chamber at a gradually decreasing rate when the engine starts, a fuel inlet to said mixing chamber, a valve controlling said fuel inlet and arranged to open when the engine is running and to close when the engine is stopped, and a delivery outlet from said mixing chamber to the engine cylinders, withdrawal of a mixture of oil and fuel from said mixing chamber when the engine starts gradually producing and maintaining a vacuum in said vacuum chamber until the engine is stopped, when oil continues to enter said vacuum chamber through said feed passage for a regulated period of time.

4. Apparatus for effecting cylinder lubrication in an internal combustion engine comprising a compartmented vessel adapted to contain lubricating oil in a reservoir forming one compartment and liquid fuel and oil in a mixing chamber forming another compartment of said vessel, a vacuum chamber in communication between said oil reservoir and said mixing chamber, means for delivering a measured quantity of oil from said reservoir to said vacuum chamber and thence to the mixing chamber when the engine is at rest, a liquid fuel inlet to said mixing chamber, a delivery outlet from said mixing chamber, and means for supplying liquid fuel to said mixing chamber through said fuel inlet to cause the proportion of oil to fuel supplied from the mixing chamber through said mixture outlet and thence to the engine induction system progressively to decrease when the engine is running.

5. Apparatus as claimed in claim 4 wherein the compartmented vessel is provided with an oil cup, an oil feed passage from said oil compartment to said oil cup, a restricted oil inlet orifice leading from said oil cup to the vacuum chamber, and valve means controlling the liquid fuel inlet to the mixing chamber, said valve means being adapted to open under withdrawal through the mixture outlet of the contents of said mixing chamber.
